UNITED STATES PATENT OFFICE.

AUGUSTO RIVELLI, OF BALTIMORE, MARYLAND, ASSIGNOR OF ONE-HALF TO JAMES D. ALAIMO, OF BALTIMORE, MARYLAND.

SHIP PROTECTOR.

Application filed November 3, 1924. Serial No. 747,642.

To all whom it may concern:

Be it known that I, AUGUSTO RIVELLI, a citizen of the United States, residing in the city of Baltimore and State of Maryland, ⁵ have invented new and useful Improvements in Ship Protectors, of which the following is a specification.

This invention relates to protecting devices for ships, an object being to provide ¹⁰ means which may be normally elevated above the water line of a ship, but which is capable of being quickly moved to a lowered position so as to be in the path of torpedoes and thus protect the hull of the ship ¹⁵ from injury.

Another object of the invention is the provision of novel and efficient means for limiting downward movement of the protector and for maintaining the protector in proper ²⁰ operative position.

With the above and other objects in view, the invention further includes the following novel features and details of construction, to be hereinafter more fully described, illustrated in the accompanying drawings and ²⁵ pointed out in the appended claims.

In the drawings:—

Figure 1 is an elevation of a ship with the invention applied.

Figure 2 is a top plan view of the same with the hull of the ship shown in outline.

Figure 3 is an enlarged fragmentary sectional view showing the protector in lowered position.

Figure 4 is a similar view with the protector raised.

Figure 5 is a fragmentary elevation showing the frame carried stop engaging means.

Referring in detail to the drawings where-
⁴⁰ in like characters of reference denote corre-
sponding parts, the hull of the ship which is indicated at H has positioned upon opposite sides a protector in the form of a frame 10. This frame encloses a suitable metal fabric ⁴⁵ or net 11 and has extending longitudinally thereof a centrally located pivot bar 12.

The frames 10 preferably extend the length of the hull H and are connected with the hull through the medium of spaced arms ⁵⁰ 13 which extend outwardly upon opposite sides of the hull. These arms have their inner ends rigidly secured upon shafts 14 and the latter are mounted in bearings ⁵⁵ 15 secured to the hull. The outer ends of the arms 13 are pivotally mounted upon the bar

12 and are provided with upwardly extending offset stop shoulders 16. The pivot bars 12 carry shoulder engaging members in the form of loops 17 which extend across the outer ends of the arms 13 between the stop ⁶⁰ shoulders 16 and the frame 10.

Mounted upon the shafts 14 are beveled gears 18 and these gears are engaged and driven by beveled gears 19 which are mounted upon the outer ends of a transversely disposed shaft 20. This shaft extends through the hull H and is driven from a motor or other suitable source of power 21 through the medium of gears 22.

The net may thus be elevated to the position shown in Figure 4 so as to be above the water line and not interfere with the progress of the ship, or it may be lowered to the position shown in Figure 3. Downward movement of the net is limited by means of ⁷⁰ chains 23 which are secured to the hull H and to the frame 10 as indicated at 24 and 25 respectively. In addition to limiting downward movement of the nets the chains 23 serve to hold the loops 17 engaged with the shoulders 16 and prevent pivotal movement of the frames while the nets are in their lowered position.

The invention is susceptible of various changes in its form, proportions and minor details of construction and the right is herein reserved to make such changes as properly fall within the scope of the appended claims.

Having described the invention what is ⁸⁰ claimed is:—

1. The combination with a ship, of a pro-
tector comprising a frame located upon each ⁸⁵
side of and spaced from the hull of the ship,
shafts extending along opposite sides of the
hull, arms having their ends rigid with the
shafts and their outer ends pivotally se-
cured to the frames, means whereby the
shafts may be rotated to raise and lower the
arms and raise and lower the frames and ⁹⁵
means for resisting pivotal movement of the
frames when the latter are in lowered po-
sition.

2. The combination with a ship, of a pro-
tector comprising a frame located upon each ¹⁰⁵
side of and spaced from the hull of the ship,
shafts extending along opposite sides of the
hull, arms having their inner ends rigid with
the shafts and their outer ends pivotally se-
cured to the frames, means whereby the ¹¹⁰

shafts may be rotated to raise and lower the arms and raise and lower the frames, offset shoulders at the outer ends of the arms, means rigid with the frames and engaging the shoulders to limit pivotal movement of the frames in one direction when the said frames are in lowered position and means connecting the frames and ship to limit downward movement of the frames and hold the rigid shoulder engaging means in contact with said shoulders.

3. The combination with a ship, of a protector comprising an elongated frame adapted to extend longitudinally upon opposite sides of and spaced from the hull of the ship, a pivot bar extending longitudinally and centrally of each of the frames, arms having

their outer ends pivotally mounted upon the pivot bars, shafts extending longitudinally of the hull upon opposite sides of the ship, 20 said shafts having a rigid connection with the inner ends of the arms, means whereby the shafts may be rotated to raise and lower the frames, stop shoulders extending upward from the outer ends of the arms, loops rigid 25 with the pivot bars and extending across the outer ends of the arms for engagement with the stop shoulders and flexible members having one of their ends connected to the upper edges of the frames and their outer ends connected to the hull of the ship. 30

In testimony whereof I affix my signature.

AUGUSTO RIVELLI.
